UNITED STATES PATENT OFFICE.

CLAUDE L. MCKESSON, OF LOS ANGELES, CALIFORNIA.

CONCRETE-TAMPER.

1,096,445.

Specification of Letters Patent.

Patented May 12, 1914.

Application filed April 5, 1913. Serial No. 759,080.

To all whom it may concern:

Be it known that I, CLAUDE L. MCKESSON, a citizen of the United States, residing in the city of Los Angeles, county of Los Angeles, and State of California, have invented a new and useful Concrete-Tamper, of which the following is a specification.

My invention relates to the construction and use of a tamper especially designed for bringing mortar to the surface of concrete in which a dense smooth or slightly roughened wearing surface is desired.

The object of the invention is to provide a suction tamper which will drive down the rock and gravel near the surface and which will bring to the surface a layer of mortar sufficiently thick to be finished with a trowel or float if desired.

The means by which these and other beneficial results are attained is illustrated in the accompanying drawings in which:

Figure 1 is a side view of one type of my tamper as it appears ready for use. Fig. 2 is a bottom plan view of the same tamper. Fig. 3 is a transverse section taken on the dotted line *a—a* in Fig. 2. Fig. 4 is a bottom plan view of a somewhat different type of tamper embodying my improvements. Fig. 5 is a transverse section taken on the dotted line *b—b* in Fig. 4 and Fig. 6 is a cross-sectional view taken at *c—c* in Fig. 5.

Throughout the several views like characters indicate like parts and referring to the details of construction 8 is a plate having numerous apertures 9 extending from its under to its upper surface. For convenience in casting these apertures are usually tapered toward the top. A handle socket 10 is integrally formed on the top of the plate.

40 This socket may be round as shown in Fig. 2 or rectangular as shown in Fig. 6.

12 is a flexible cover corresponding in size and shape to the top of the plate 8 and is provided with a centrally located aperture 45 corresponding to the size and shape of a cross section of the handle socket. This cover 12 may be constructed of cloth, carpet, rubber or similar material. Rubber is especially adapted to the use and is preferred.

50 In the type of my device shown in Figs. 1, 2 and 3 the flexible covering is loosely secured to the top of the plate 8 by means of screws 17. Wires, rivets or other simple expedients may be used to accomplish the same

55 result.

11 is an ordinary tamper handle.

In the modified form of my device shown in Figs. 4, 5 and 6, the flexible cover is weighted down by means of a sheet of metal 13 resting upon it. In this form of construction the flexible cover and the metal weight 13 are prevented from turning by being fitted around the angular socket 10 provided for the handle. The fit around the handle socket is sufficiently loose to allow the flexible cover and the weight to move freely up and down. In some work where it is desirable that the tamper shall have the maximum amount of suction power it is found desirable to provide rims around each 70 aperture. These rims are designated in the drawings as 14 and a similar rim 15 surrounds the plate 8. These thin rims may be driven deeper into the concrete than the face of the tamper would otherwise penetrate 75 and allow the tamper to be raised higher before air can enter under the tamper and release the partial vacuum produced by the raising of the tamper.

When concrete is intended to receive a 80 unfinished or dense wearing surface it is usually mixed and moistened until the sand and cement filling the spaces between the coarser particles is in a liquid or semi-liquid state and the best results are attained where this 85 condition exists. After concrete, so mixed, is spread and its surface shaped into the desired form it is ready for tamping with my tamper. When the tamper is dropped on the concrete the rock and coarse aggregate 90 is driven down and the mortar displaced thereby rises partially filling the apertures in the plate. The portion of the air in the apertures displaced by the mortar escapes under the flexible cover. At the end of the 95 downward stroke the flexible cover falls, valve like, as a result of gravity and momentum, and closes the tops of the apertures. As the tamper is raised air is prevented from entering the tops of the apertures by the 100 flexible cover and atmospheric pressure prevents the mortar from escaping until air entering under the tamper relieves the partial vacuum so created. The mortar within the apertures at the beginning of the 105 upward movement of the tamper is raised an appreciable distance before the vacuum is thus relieved and capillary attraction between the mortar raised and the mortar in the concrete lifts more mortar to the surface of the concrete. Several short quick strokes with this tamper will provide all the 110

mortar ordinarily required for troweling or floating. The action of the tamper in drawing the mortar up out of the concrete resembles the action of a lift pump having a suction inlet. The raising of the tamper lifts mortar in the apertures and draws up more. At the next stroke the mortar is thicker on the surface and rises higher in the apertures. With several strokes the mortar may be 10 brought up until the apertures are filled and the mortar is forced out under the flexible cover. The rims around the apertures delay the entrance of air under the tamper until it is withdrawn farther than otherwise and by 15 thus lengthening the "stroke" increases the pumping capacity of the tamper.

Variations may be made in the construction of the tamper and by substituting some of the ordinary forms of valves for the flexible cover but the construction shown is preferred. Broadly the idea of a tamper having mechanically created vacuum and the method of bringing mortar to the surface of concrete by the use of such a tamper, which 25 may reasonably be termed a suction tamper, is thought to be new and novel and

Having thus disclosed my invention what I claim as new and desire to secure by Letters Patent is.

20 1. A concrete tamper having apertures for the reception and retention of mortar on the surface of the concrete being tamped and means for closing the tops of said apertures

when the tamper is lifted thereby producing suction adapted to bring more mortar to the 35 surface of the concrete.

2. A concrete tamper consisting of a handle; a plate attached to said handle; apertures in said plate and means for closing said apertures, all substantially as described. 40

3. A concrete tamper consisting of a handle; a plate attached to said handle; apertures in said plate and a flexible cover adapted to close said apertures, substantially as 45 described.

4. In a concrete tamper, the combination of a handle; a plate attached to said handle; apertures in said plate; a flexible cover on said plate adapted to close the tops of said apertures at the end of the downward stroke 50 and means for keeping the said flexible cover in operative position, all substantially as described.

5. In a concrete tamper, the combination of a handle; a plate attached to said handle; apertures in said plate; rims around the bottom edges of said apertures, and a flexible cover adapted to close said apertures at the 55 end of a downward stroke, all substantially as described.

Signed in the presence of two subscribing witnesses.

CLAUDE L. MCKESSON.
